BENJAMIN FLOWERS, OF JERUSALEM, OHIO.

Letters Patent No. 85,082, dated December 22, 1868.

IMPROVEMENT IN SHINGLING ROOFS.

The Schedule referred to in these Letters Patent and making part of the same.

To all whom it may concern:

Be it known that I, BENJAMIN FLOWERS, of Jerusalem, in the county of Monroe, and State of Ohio, have invented a new and useful Improvement in Shingling Roof-Angles; and I do hereby declare that the following is a full, clear, and exact description thereof, which will enable those skilled in the art to make and use the same, reference being had to the accompanying drawings, forming part of this specification.

This invention relates to a new and improved method of shingling the gutters, "valleys," or angles formed by the joining of roofs, whereby all leakage is prevented, without any important increase in the expense; and

The invention consists in the method of applying angular metallic plates to said gutters or "valleys," as will be hereinafter more fully described.

The drawing represents a perspective view of a roof-gutter or angle, formed by the intersection of two roofs covered according to my invention.

Figure 2 is a detached view of one of the angular metallic pieces which are used in combination with the shingles.

Similar letters of reference indicate corresponding parts.

A and B represent the two roofs, which intersect or joint, and form an angle or gutter.

C represents the shingle, and

D represents the metallic sections.

To make this portion of a roof water-tight with shingles, has hitherto been considered a very difficult performance.

If a long metallic gutter is used, a good deal of ex-

penuse must be incurred, and its decay or failure in any one part destroys the whole.

By commencing and laying up, with the shingles, the metallic sections or angular pieces D, the job becomes an easy one, and the expence trifling, while, in case of the failure of a single piece, repairs are readily made, but in that event no leakage can occur.

Instead of a single thickness of metal, as in the case of the continuous metallic gutter, I have the angle protected by two, three, or four thicknesses of metal, according to the length of the sections, thus rendering the gutter or "valley" as perfectly water-proof and durable as any part of the roof.

In this example of my invention it will be seen that the metallic sections are laid up with the shingles on one roof, and that the shingles on the other roof are laid on, and cover the wing of the section which extends on to that roof.

I claim as new, and desire to secure by Letters Patent—

The angular metallic sections D, connecting the gutters or "valleys" of two roofs together, when applied as described, by having one wing of each of the sections laid up with the shingles on one roof, and the other wings of the same resting upon each other, and covered by the shingles on the other roof, as herein shown and described.

BENJAMIN FLOWERS.
